APPARATUS FOR GUIDING FLEXIBLE
TUBULAR FABRICS

Julien Dungler, Basel, Switzerland

Application February 11, 1950, Serial No. 143,716
In France November 18, 1949

18 Claims. (Cl. 26—55)

1

The present invention relates to an apparatus for guiding flexible tubular fabrics and similar fibrous articles or objects.

In the apparatus according to my copending application Serial No. 138,684, filed January 14, 1950, the flexible or stretchable tubular fabric or article is in contact at its lateral folded ends with external guide means rotatably held at a fixed location and with internal guide means freely rotatable inside the tubular fabric, the apparatus further including means acting upon the internal guide means through the tubular article to hold the internal guide means in a position in which the latter cooperates through the tubular article with the external guide means.

It has been found that, in certain instances, the performance of such an apparatus can be further improved and extended to further utilization, particularly where the apparatus is used for the enlargement of tubular articles in a direction transverse to the longitudinal axis thereof.

It has further been found that undesirable wrinkles or creases sometimes occur along the diverging edges of the tubular article between the point or location where the article leaves the guiding apparatus and the point of positive entrainment by a succeeding feeding or pick-up device.

It is, therefore, an object of the present invention to provide means ensuring avoidance of the heretofore mentioned drawbacks in guiding apparatus for tubular textile articles.

Another object of this invention is to provide means facilitating a considerable simplification of the apparatus by holding in place the external guide means without the need of separate retaining means therefor.

A further object of the invention is to provide means keeping the tubular article in shape and preventing undesirable creasing until it reaches a point of positive entrainment.

Still another object of the invention is to provide means affording severance or cut of the tubular article along its fold line or lines as said article passes through the guiding device.

In order to attain the above and other objects that will subsequently appear, the invention according to one of its aspects provides means for guiding flexible tubular articles, freely movable internal guide means being disposed including an inner member rotatable inside the tubular article, and external guide means including a rotatable outer member positioned to coact with the inner member through said tubular article in a sense urging said inner member toward the

2

periphery of the tubular article, thereby effectively locking the inner member between the tubular article and the outer member.

According to another feature of the invention, 5 the apparatus also includes supporting means positioned externally of the tubular article to provide a rest for the innermost portion of the inner member, positioned remotest from the outer member.

10 The external supporting means referred to may include, according to a further feature of the invention, an outer roller cooperating with an inner roller which in turn is associated with the internal guide means, the tubular article in passing between the rollers causing them to rotate so that gliding movement or slippage of the tubular article from the supporting means is effectively avoided.

According to still another feature of the invention 15 internal supporting means are contemplated to which the inner roller may be attached, the internal supporting means having preferably secured thereto rotatable inner members, spaced in longitudinal direction of the tubular article, the 20 internal supporting means being adapted to guide the tubular article substantially beyond its point of contact with the last one of the rotatable inner members. Each inner member may in this case consist of two rotary elements disposed 25 on opposite sides of the internal supporting means and having a common pivot secured thereto.

According to a further feature of the invention, 30 slitting means are preferably provided on the internal guide means, e. g. on the internal supporting means forming part thereof.

The above and other objects, features and advantages will become apparent from the following description, reference being had to the accompanying drawings in which:

Fig. 1 is a front elevation, partly in section, of an apparatus embodying one form of the invention;

Fig. 2 is a section taken along line 2—2 of Fig. 1;

Fig. 3 is a view similar to Fig. 2 taken on the line 3—3 of Fig. 4, showing another embodiment of the invention;

Fig. 4 is a view similar to one half of Fig. 1 but showing the apparatus modified;

Fig. 5 is a top plan view of the apparatus shown in Figs. 3 and 4; and

Fig. 6 is a section, on a larger scale through an inner rotatable member used according to Figs. 3—5.

Referring now more particularly to the draw-

ings, there is disclosed in Figs. 1 and 2 a pair of carriages 2, 2' mounted on a common guide rail (not shown) for relative displacement in a direction transverse to the longitudinal axis of the tubular article to be treated, thereby allowing adjustment of the apparatus to articles of different width. The two carriages 2, 2' support identical assemblies arranged symmetrically to each other, of which only the one supported by the carriage 2 will be more fully described.

Extending upwardly from the carriage 2 is an elbow-shaped member 31 carrying the shafts 32 and 33, respectively, of two rollers 18 and 19. These rollers are preferably provided with a peripheral cover or strip of elastic material, such as indicated at 18a for the roller 18. The shaft 32 of the roller 18 is fixed upon the elbow member 31 while the shaft 33 of roller 19 is slidable in the direction of arrows 37a, 37b in a slot 34 provided in member 31. The shaft 33 may be affixed in a selected adjusted position by means of a handle 35 which is screwed upon the threaded outer end of this shaft 33; tightening of the handle 35 causes a shoulder 36 to bear upon the underside of the portion provided with slot 34. The displacement of the shaft 33 in the direction of arrow 37b is limited by an adjustable stop 38.

The tubular article to be guided, e. g. a knitted fabric, is shown at 9. As clearly apparent from Fig. 1, this fabric is guided and maintained in position at two parallel fold lines between rollers 18, 19 and 18', 19', respectively, without further need of other retaining means.

The left-hand fold line, as viewed in Fig. 1, is formed by a portion of the fabric which passes between the rollers 18, 19 and a freely movable and floating hollow inner ring member 6, preferably provided with a slit 6a to increase its resiliency; analogously, the right-hand fold line is formed by a portion of the fabric which passes between the roller 18', 19' and a similar hollow inner ring member 6'.

It will be noted that, in contradistinction to the apparatus disclosed in the above-identified application, the ring 6 engaging the fold line of the fabric is held against outward displacement by the fabric itself and is held against inward displacement by the rollers 18 and 19, without the need of any additional retaining means.

The innermost portion of the floating ring member 6, opposite to the one cooperating with the rollers 18 and 19, rests on a table 41 which is supported by an arm 40 integral with the carriage 2.

The arrangement just described is used in the following manner: The rings 6, 6' are inserted into the tubular fabric. The handles 35, 35' of the two roller adjustment devices are loosened, and the rollers 18, 19' are displaced in the direction of arrow 37a into an extreme position in which they are temporarily retained upon tightening of the handles. Thereupon, the tubular fabric 9 is put into place so that the rings 6, 6' occupy the position shown in the drawings.

The handles are then again loosened and the rollers 18, 19' placed in the position as illustrated, by displacing them according to arrow 37b and in abutment with stops 38, 38', so as to cause said rollers to cooperate with the fixed rollers 18, 18' at the inner peripheral portions of the rings 6, 6', thereby maintaining the rings 6, 6' in place and insuring the proper guidance of the tubular fabric 9 between the rollers 18, 18' and 19, 19' on the one hand and the rings 6, 6' on the other hand.

The modification shown in Figs. 3-6 is particu-

larly applicable to elastic tubular textile objects or articles which are to be guided over a considerable length of their path, as, for example, up to a location in immediate proximity of a feeding or pick-up device.

In this form of the invention each of the removable internal guide means, respectively, located at the two fold lines of the tubular fabric or article 9, comprises two coupled, freely and loosely rotatable members 43, 44 spaced apart with respect to the longitudinal direction of the fabric, these members being journaled upon a common support 45. In order to prevent the fabric 9 from making contact with the support 45, each of the rotatable members 43, 44 is subdivided into two parts or elements disposed symmetrically with respect to the support 45, respectively above and below the latter, as best seen in Fig. 6 illustrating in greater detail member 44. This member consists of two halves 44a, 44b positioned on opposite sides of the support 45 which latter, as shown, is preferably in the form of an elongated, thin plate provided with cutouts to reduce its weight. The elements 44a, 44b are rotatably supported on the plate support 45 by means of ball bearing 39 lodged in a circular cutout 46 of the plate support.

Each of these elements is provided with a hub, 44c and 44d, respectively, from which arms or spokes extend toward its periphery as indicated at 44e (Fig. 5) for the upper member half 44a, thus affording the necessary mechanical connection and unity. The two halves are held together by a threaded stud 54 and a pair of nuts 53.

The elements of ring 43 corresponding to the parts 44a-44e of ring 44 have been indicated at 43a-43e, respectively.

The rotatable inner ring members 43 and 44 are adapted to cooperate with the outer rollers 18a, 19a and 18b, 19b, respectively, in manner similar to rollers 18, 19 and ring 6 (Figs. 1 and 2); rollers 19a, 19b being adjustably mounted as already described with respect to roller 19.

The two pairs of outer rollers 18a, 19a and 18b, 19b, respectively, associated with the ring members 43 and 44, mounted on their common support 45, are carried upon a base 42 fixed to the carriage 2 which is transversely slidable in the manner mentioned above. The base 42 is furthermore provided with vertical lugs 47 in which is journaled a horizontal shaft 48 carrying an idler roller 49, the latter being adapted to cooperate with a roller 50 freely rotatable upon a shaft 51 which is rigid with the support 45. As explained with respect to the former embodiment, there will be a separate guiding assembly (such as shown in Figs. 3-6) comprising each a pair of rotary members 43, 44, freely movable inside the tubular fabric article with their support 45, and two pairs of outer rollers mounted on the stationary base 42 for engagement with the fold lines of the tubular fabric 9.

The plate 45 supporting the ring members 43, 44 is provided with an extension 52 designed to guide the tubular fabric 9 (which is assumed to advance in the direction of arrow 55) beyond its zone of contact 53 with the second ring member 43, and up to a point or location close to a pick-up device indicated schematically at 57 (Fig. 5).

The aforesaid arrangement or guide system described in connection with Figs. 3-6 is employed in the following manner: The two removable and loosely floating assemblies 43-44-45 are inserted into the tubular article or object which, after displacement of the upper rollers 19a and 19b into

their extreme positions, is placed in position as illustrated in Fig. 4, whereupon the upper rollers are brought into engagement therewith as previously described. These rollers are retained in this position by suitably manipulating the handles 35a, 35b, as is self-evident from Fig. 4.

If a feeding movement is imparted to the article 9 by, say, a set of draw rollers (not shown) provided in the device 57, the article is enlarged to an extent determined by the position of the carriages 2 upon their guide rail. The article 9 by its movement causes the ring members 43 and 44 as well as the rollers 18a, 19a and 18b, 19b to rotate and to reduce friction with the fabric to a minimum, inward displacement of the ring members being again prevented by the outer rollers whereas outward displacement thereof is prevented by the article 9.

The lower portion of the tubular article 9 passes between the idler rollers 49, 50 which are set in rotary motion thereby, thus avoiding slipping off or gliding movement of the fabric article between these idler rollers; the plate support 45 carrying the rings 43, 44 rests upon the roller 49 through the intermediary of roller 50, as explained hereinabove.

It is to be noted that the guide extension 52 positively maintains the spread of the fabric throughout substantially the entire zone extending between the second ring member 43 and the pick-up device 57, thereby preventing the formation of any wrinkles or creases as the article 9 passes from the guiding apparatus to the pick-up device.

The arrangements described may be utilized for a number of purposes. Thus, they may be embodied in an apparatus for simply guiding a fabric or other tubular piece of material along a predetermined path, for example across a drying rack. In this case, a number of devices of the character described may be positioned in alignment with one another, along each of the two fold lines, throughout the path traversed by the material.

The invention, particularly in the form described in Figs. 3 to 6, may further be utilized in apparatus for enlarging a tubular fabric or other material to a predetermined width. In this case, the common support 45 with its ring members 43, 44 may be disposed at an angle to the longitudinal axis of the travel of the tubular article treated.

The apparatus described may also be utilized to sever the tubular fabric along one or more of its fold lines. Suitable cutting means may for this purpose be provided on the internal guide means; thus the guiding extension 52 may removably carry, for example, a cutting edge 56 as indicated in dot-dash lines in Fig. 5. A similar effect may be obtained by equipping, for example, the ring 6 of Figs. 1 and 2 with a peripheral sharp cutting edge (not shown).

It should be understood that the embodiments of the invention described above and shown on the drawings have been given merely by way of illustration and not of limitation, and that the arrangement, nature, form and connection of the different instrumentalities may be modified in various ways without exceeding the scope of the invention. Thus, the ring members 43 and 44 may be interconnected by a steel belt or other linkages for the purpose of insuring uniform traction and guidance at both of these members. Also, it will be possible to provide a larger number of assemblies (such as shown in Figs. 3-5) e. g. three assemblies, disposed in planes extending at, say, 120 degrees to one another, so as to provide

three end fold lines formed on a tubular article of triangular cross section. Cutting means such as 56, may then be used to divide and cut the fabric article or other textile material in three or more portions of equal or different width or dimensions. Furthermore, the ring members 43 and 44 may have different diameters, and the guide extension 52 may be provided with roller means to substitute rolling engagement for sliding engagement.

Having thus described the invention, what is claimed as new and desired to be secured by Letters Patent, is:

1. In a guide apparatus for flexible tubular textile articles, in combination, a support, a lower and an upper roller mounted on said support, adjusting means for varying the separation of said rollers and for fixing said rollers in a relatively inclined position, a ring member adapted for horizontal position with its inner periphery in engagement with both said rollers when the latter are in said relatively inclined position, and an extension on said support forming a rest for a portion of said ring member when engaged by said rollers.
2. In an apparatus for guiding a flexible tubular fabric article, in combination, a support, a pair of rollers mounted on said support, adjusting means for varying the separation of said rollers and for fixing said rollers in a relatively inclined position, a plate independent of said support, and a ring member journaled upon said plate, said ring member comprising two annular elements positioned on opposite sides of said plate and being adapted for position with the inner peripheries of said annular elements, respectively, in engagement with said rollers when the latter are in said relatively inclined position.
3. In an apparatus for guiding a flexible tubular article, in combination, a support, pairs of rollers mounted on said support, adjusting means for varying the separation of the rollers of each of said pairs and for fixing the rollers of each pair in a relatively inclined position, a plate independent of said support, and a plurality of ring members journaled upon said plate, said ring members being positionable with their inner peripheries in engagement with the rollers of respective pairs when the latter are in said relatively inclined position.
4. The combination according to claim 3, wherein said plate is provided with an extension forming guide means substantially aligned with the peripheries of said ring members and extending beyond an outermost one of said ring members.
5. The combination according to claim 3, wherein said support is provided with an extension forming a rest for a portion of said plate.
6. The combination according to claim 5, wherein said portion is provided with a rotatably supported first roller, and said extension is provided with a rotatably supported second roller positioned to cooperate with said first roller.
7. The combination according to claim 3, wherein each of said ring members comprises a pair of annular elements being engaged by a respective roller of the associated pair of rollers.
8. A guide apparatus for tubular textile articles comprising internal guide means each having an inner peripheral portion and arranged for location inside said tubular article and adapted to loosely and floatingly engage the latter, and external guide means positioned to bear through

said tubular article against and to coat with said internal guide means at said inner peripheral portions, to thereby guide said internal guide means from therewith toward said tubular article and to thus effectively maintain said tubular article in position between said internal guide means and said external guide means.

9. A guide apparatus for moving tubular textile articles comprising internal guide ring means arranged for location inside said tubular article and adapted to loosely rotate therein, said internal guide means being each provided with an inner peripheral portion and movable substantially in the same plane in which said tubular article moves, and external guide means positioned to engage through said tubular article said internal guide means at said inner peripheral portions and to retain said internal guide means against said tubular article, thus effectively maintaining said tubular article in position remote from said external guide means.

10. An apparatus according to claim 9, comprising a stationary support fixedly mounted externally of said tubular article, said internal guide means being substantially horizontally disposed with a portion thereof and remote from said external guide means, resting upon said support when said internal guide means is engaged by said external guide means.

11. An apparatus according to claim 9, wherein said internal guide means is provided with a cutting edge positioned to penetrate said tubular article when the latter is engaged by said internal and said external guide means.

12. An apparatus according to claim 9, wherein said internal guide means is provided with a guide extension having an edge extending substantially tangentially of said internal guide means.

13. An apparatus according to claim 12, wherein said extension is provided with a cutting edge

projecting outwardly from said tangentially extending edge.

14. An apparatus according to claim 9, comprising a stationary support fixedly mounted relative to said external guide means and externally of said tubular article, said internal guide means including a supporting element provided with a portion resting upon said support when said internal guide means is engaged by said external guide means.

15. An apparatus according to claim 14, wherein said portion comprises a horizontal shaft, and a first roller rotatable on said shaft and engageable with said support.

16. An apparatus according to claim 15, wherein said support comprises a second roller positioned to cooperate with said first roller.

17. In a guide apparatus for flexible tubular textile articles, in combination, a support, a lower roller and an upper roller mounted on said support, and a ring member arranged for location within said tubular article and loosely rotatable therein, said lower and upper rollers being positioned for engagement with the inner periphery of said ring member, to thereby guide said tubular article past said ring member.

18. In a guide apparatus according to claim 17, including a guide extension associated with said ring member and tangentially extending therebeyond.
